UNITED STATES PATENT OFFICE.

JEAN JACQUES AND ALLEN R. COSGROVE, OF YORK, PENNSYLVANIA, ASSIGNEES TO
MARTIN-PARRY CORPORATION, OF YORK, PENNSYLVANIA, A CORPORATION OF
DELAWARE.

ICE TRAY FOR ELECTRICAL REFRIGERATION.

Application filed March 25, 1927. Serial No. 178,899.

This invention relates to ice trays for use in automatic refrigeration.

The primary object of the invention is to provide a cover for the ice tray used in 5 mechanical refrigeration to protect the ice and water within the tray from contamination, which ordinarily occurs during the defrosting operation.

A further object of the invention is to 10 secure the cover to the grid as distinguished from inserting the grid into the bottom of an open pan.

A further object of the invention is to 15 construct the grid by bending a strip of metal intermediate its length at a plurality of points to define a cellular structure, functioning to separate the ice into cube formation.

Another object of the invention is to 20 provide the cover with an downwardly extending flange, around its peripheral portion, to function as a water shed for the water drippings occasioned by the defrosting operation or by spillage when inserting a super- 25 imposed tray of water into the freezer.

Another and more specific characteristic 30 of the invention resides in the spot-welding of the grid to the under-surface of the cover, thus rendering the construction of the device 35 very economical.

Numerous other objects of the invention 40 will be apparent to those skilled in the art from a reading of the following specification, in conjunction with the drawings attached hereto and forming a part hereof in which—

Fig. 1 represents a top plan view,

Fig. 2 is a longitudinal sectional view on lines 2—2 of Fig. 1,

Fig. 3 is a cross-sectional view,

Fig. 4 is a detailed view partly in section of the grid and top structure,

Fig. 5 is a top plan view of a variant form of cover,

Fig. 6 is a side view of this cover and grid structure,

Fig. 7 is a detailed view on line 7—7 of Fig. 5, and

Fig. 8 is a still further modified form of 50 cover.

Referring now more specifically to the drawings, reference numeral 1 designates an ice tray which is open at its top. This ice

tray has side walls 2 and end walls 3. To the end walls we secure, by soldering or 55 spot welding, a front piece 5 having a finger gripping portion 6.

As distinguished from the open top type of ice pan now conventionally used, we employ a cover 7 to which is secured the grid 8. This cover is provided with a downwardly extending flange around its peripheral portion as designated by reference numeral 9 thereby to serve as a water shed against drippings or spillage caused by defrosting or the insertion of a superimposed tray. The grid structure can be constructed in any manner desired, or of any materials, but we preferably form the same of metal 15 intermediate its ends at a plurality 70 of points to define a multiplicity of downwardly extending partitions, constituting a cellular grid to separate the formed ice into numerous cubes of the required dimensions. This grid is designated by reference numeral 75 10, which is bent to provide the partitions 11 and forming a plurality of cells 12. We have found it to be desirable to secure the grid to the under-surface of the cover by spot-welding as at 14, although, of course, 80 any other manner of securing the grid to the cover or of forming the grid integral with the cover can be used without departing from the invention.

The cover is preferably provided with 85 several longitudinal corrugations as designated by reference numeral 15. This structure of cover and grid lends itself particularly well to the separation of the ice from the cell portions. 90

It will be noted that the partition 16 is of relatively short length and this abuts against an end of the tray.

Referring to the modification shown in Figs. 5 and 6, it will be noted that the peripheral flange has been omitted, and that a cut-out portion 17 is provided for the insertion of the finger of the operator or of a device to separate the cover and grid from the tray. The modification shown in Figure 100 8 is substantially the same as discussed in detail in connection with the preferred form of the invention, but includes upstanding longitudinal marginal flanges to define, in conjunction with the top or cover, a water trough for receiving heated water, serving 105

to cause an easy separation of the ice cubes from the grid.

It will be obvious that many changes in the construction and arrangement of the parts may be made by those skilled in the art without departing from the spirit of the invention as defined in the following claims.

Having thus described the invention, 10 what we claim is:

1. A tray for automatic refrigeration comprising an open-faced receptacle, a grid for fitting into the confines of said receptacle, said grid comprising a strip of metal bent 15 intermediate its ends to define a plurality of partitions for separating the ice to be formed in cubular formation.

2. A tray for automatic refrigeration, comprising an open-faced receptacle, a unitary grid and cover structure for said receptacle, and adapted to be inserted into the receptacle, said cover having downturned longitudinally extending flanges surrounding at 25 least a portion of the receptacle to thereby function as a water shed therefor.

3. A tray for automatic refrigeration comprising a receptacle, a grid structure for said receptacle, said grid structure being formed by bending a length of metal intermediate 30 its ends to define a plurality of partitions, a cover spot-welded to said grid

structure, and forming a unitary part thereof, said cover protecting the contents of the receptacle from foreign substances.

4. A tray for automatic refrigeration comprising a receptacle, an end portion secured to said receptacle and having a finger grip therefor, a grid structure, and a cover secured thereto and forming a unitary part thereof, said cover constituting a means to prevent extraneous matter from entering the receptacle, said cover when in operative position being located at a plane lower than the marginal upper portion of the said end piece. 35 40 45

5. A tray for automatic refrigeration comprising a receptacle, a grid structure for said receptacle, such grid structure being formed by bending a strip of metal intermediate its ends to define a plurality of partitions, a cover rigidly secured to said grid structure and forming a unitary part thereof, and constituting a protecting medium for the contents of the receptacle from foreign substances, said cover having a cut-out portion 50 55 for receiving the fingers of the operator to separate the cover and grid from the tray.

In testimony whereof we affix our signatures.

JEAN JACQUES.
ALLEN R. COSGROVE.
